UNITED STATES PATENT OFFICE.

JOSEPH FRANK, OF NEW YORK, N. Y., ASSIGNOR TO THOMAS L. GREEN, OF NEW YORK, N. Y.

COAL-HOLE COVER.

1,252,795.

Specification of Letters Patent.

Patented Jan. 8, 1918.

Application filed July 21, 1916. Serial No. 110,583.

To all whom it may concern:

Be it known that I, JOSEPH FRANK, a citizen of the United States, residing at New York, in the county of New York and State 5 of New York, have invented certain new and useful Improvements in Coal-Hole Covers, of which the following is a specification.

This invention has relation to improvements in what are commonly known as coal 10 hole covers of the type usually located on sidewalks and similar places, and by which access may be had to a coal opening leading directly to a place of deposit for coal, or establishing communication with a conduit 15 or passage leading to the point of deposit.

The object of the invention has been to devise a coal hole cover equipped with guard 20 means for safety purposes and of such a construction that when the cover is opened said means will prevent pedestrians from 25 stepping into the hole which is partially inclosed thereby. Furthermore, when the cover is in its normal position, it is impossible for a person to be catapulted into the coal hole or opening. The guard means is 30 also adapted to prevent the scattering of the coal over the sidewalk or other places where the coal opening may happen to be provided.

Still another object of the invention is the 35 production of guard means of the nature above set forth, which guard means is so connected with the coalhole cover that when the latter is raised and caused to assume its open position, the guard means will at the same time be raised into an operative position whereby to secure the results previously mentioned.

With the foregoing and other objects in 40 view a complete understanding of the present invention will be had upon reference to the following detail description, and to the accompanying drawings, in which:

Figure 1 is a sectional view of a pavement 45 such as is provided adjoining a building, a coal hole being illustrated with a cover and guard means constructed in accordance with the invention, and a passage or conduit leading from the coal hole proper to a point 50 within the building where the coal is intended to be deposited.

Fig. 2 is an enlarged sectional view of the coal hole and cover means bringing out more fully the manner in which the guard means

is secured to the cover, dotted lines illustrating the parts in their open position. 55

Fig. 3 is a plan view showing the parts illustrated in Fig. 2, with the cover in open position.

Fig. 4 is a perspective view of a modified 60 adaptation of the invention in which the cover and guard means are equipped with a top guard plate in addition to the side or cheek pieces or guard members which latter only are illustrated in the preferred con- 65 struction of the invention.

Fig. 5 is a perspective view of still another modification of the invention.

Referring to the drawings, and particularly describing the invention in its details, 70 A denotes a pavement and B the wall of a building adjacent thereto. C designates the curb of the pavement and 1 the coal hole which is customarily located as near to the curb as practicable for the obvious purpose 75 of facilitating the introduction therein of the coal or other material to be deposited, directly from a wagon or the like located on the street. From the coal hole 1 a conduit 2 leads to a point within the building 80 having the wall B aforesaid. Said coal hole 1, however, may be otherwise located, as by being directly over the coal shaft, the particular location of said coal hole not being material or essential to the invention. 85

The coal hole 1 has the customary metal lining 3, seen best in Figs. 1 and 2, a cover frame 4 being situated at the upper end of the lining and seated on the latter preferably. The frame 4 is formed with a seat 4^a 90 in its upper side, in which the cover 5 is adapted to rest when closed, said cover then being flush with the surface of the frame and the surface of the pavement A as well known in this art. The seat 4^a referred to 95 is provided by the formation of a lateral flange 6 extending from the inner side of the frame 4 on all four sides of said frame.

The cover 5 is preferably of the hinged type, being hinged at its inner edge portion 100 as at 7, and therefore, adapted to be raised at the outer edge so as to swing backwardly away from the curb C as depicted in dotted lines in Fig. 2. On its under side the cover 5 is formed with flanges 5^a and seated 105 against these flanges and therefore somewhat spaced from the under surface of the cover, is the attaching member 8 of the

guard means forming the essential features of the invention. Said attaching member 8 has the side or cheek pieces 8' formed therewith and located in spaced relation so that when the cover 5 is raised into its open position the said cheek pieces 8' together with the parts 8 and 5 inclose the space above the coal hole 1 on three sides. Owing to the formation of the parts of the 10 guard means as stated, it is obvious that when the cover 5 is in raised or open position, coal or other material thrown into the coal hole 1 will be very readily directed into the hole and prevented from scattering over the pavement or sidewalk A in the objectionable manner so frequently noticed incident to the use of coal holes today. It is contemplated that the guard means shall 15 be secured in any substantial manner to the under side of the cover 5, the attaching portion 8 being bolted or otherwise secured to the cover by fastenings such as indicated at 9 in Fig. 2, any suitable number of which fastenings may be employed. The attaching portion 8 is seated directly against the flanges 5^a and it is obvious that should occasion require renewal of the guard means, such operation may be expedited by the removal of the fastenings, such as 9, and the 20 replacement of a new guard device, such as is comprised by the parts 8 and 8'. In order to limit the opening movement of the cover 5, the guard means aforesaid is supplied with a stop in the form of a cross 25 bar or strap 10, the ends of which are suitably and rigidly secured to the opposite lowermost corner portions of the cheek or side pieces 8'. This stop 10 performs its stop function by abutment with the outermost portion of the flange 6 forming the seat 4^a for the cover 5, and it will be noticed from the drawings that the side pieces 8' of the guard means are downwardly and inwardly elongated whereby it is possible to 30 open the cover 5 sufficiently to permit said cover to lean rearwardly with respect to a perpendicular plane coincident with the innermost wall of the coal hole 1. Under these conditions the weight of the cover is 35 sufficient to maintain it in an open position once it has been raised so as to assume the said position illustrated by the dotted lines in Fig. 2. The foregoing advantage is secured, owing to the construction which may 40 otherwise be described as involving the location of the stop 10 a greater distance from the outermost portion of the flange 6 or seat 4^a than an arc of 90° of movement of the cover 5. 45 The stop 10 not only performs its stop function but constitutes a brace intermediate the parts 8'. 50

In Fig. 4 is represented a further embodiment of the invention in which the construction previously described is supplemented 65 by the provision of an auxiliary top guard plate 8", the latter having edge flanges riveted or otherwise fastened to the side pieces 8' aforesaid at the front edges of the latter. When the cover of the modified construction 70 is opened, it will be apparent that the space above the coal hole 1 will be inclosed not only at the three sides, as previously suggested in regard to the preferred construction of the invention but at the top as well. 75 The space between the parts 8' is, of course, sufficient to readily allow the chute from a coal wagon or similar supply vehicle being positioned with its lower end between said parts. 80

It is contemplated within the purview of the invention to dispense with the attaching portion 8 of the guard means and secure the side members or cheek pieces 8' directly to flanges 8" on the under side of the cover 85 or lid 5, the securing means being rivets or any suitable fastenings. A handle 5^x of any conventional type may be provided for the cover 5.

Having thus described my invention, what 90 I claim as new is:

1. Coal hole covering means comprising a frame, a cover adapted to be seated on said frame and formed on its under side with flanges, guard means comprising an attaching portion seated on said flanges and spaced from the cover, said attaching portion being formed with integral side pieces disposed in spaced relation and projecting downwardly from said cover, fastenings 100 connecting said attaching portion with the cover, and a stop comprising a member connecting the lowermost portions of said side pieces and adapted to abut with the frame to limit the opening movement of the cover. 105

2. Coal hole covering means comprising a horizontal frame adapted to be positioned in a coal hole, a cover seated on the frame, guard means carried by the under side of said cover and comprising spaced side 110 pieces projecting downwardly from the cover and adapted to move upward as the latter is opened so as to assume guard positions at opposite sides of the coal hole, the said side pieces being formed so that their lower extremities are of such a distance from the free end of the cover as to permit opening movement of the cover through an arc greater than 90°, and stop means on the lowermost portions of said side pieces 115 co-operative with the frame to limit the extent of said opening movement.

In testimony whereof I affix my signature.

JOSEPH FRANK.
